UNITED STATES PATENT OFFICE

CHARLES L. KRUM AND HOWARD L. KRUM, OF CHICAGO, ILLINOIS, ASSIGNEES TO
MOKRUM COMPANY, OF CHICAGO, ILLINOIS, A CORPORATION.

PERFORATOR FOR FORMING TELEGRAPHIC TAPE.

1,182,179.

Specification of Letters Patent.

Patented May 9, 1916.

Application filed September 8, 1914. Serial No. 860,714.

To all whom it may concern:

Be it known that we, CHARLES L. KRUM and HOWARD L. KRUM, citizens of the United States, and residents of Chicago, county of Cook, and State of Illinois, have invented certain new and useful Improvements in Perforators for Forming Telegraph Tape, of which the following is a full, clear, and exact description.

10 The invention relates to apparatus for forming telegraph tape and seeks to provide a simple, improved key-board machine for rapidly forming the tape.

The invention consists in the features of improvement hereinafter set forth and illustrated in the preferred form in the accompanying drawings, and more particularly pointed out in the appended claims.

20 In the drawings, Figure 1 is a plan view of the improved apparatus. Fig. 2 is a vertical section on the line 2—2 of Fig. 1. Fig. 3 is an inverted plan view of a portion of the apparatus. Fig. 4 is a detail section on lines 4—4 of Figs. 3 and 6. Fig. 5 is a section on the line 5—5 of Fig. 1. Fig. 6 is a partial plan view with parts broken away and other parts shown in section. Fig. 7 is a detail section on line 7—7 of Fig. 6.

25 The several parts of the machine are mounted upon a hollow cast-metal base 10, having a depressed front portion 11. Above the depressed front portion the base is provided with an opening through which the forward ends of a series of key levers 12 extend. At their rear ends the key levers are mounted upon a fulcrum rod 13 that is suitably supported in the base 10. The forward ends of the key levers extend through a guiding comb-bar 14 fixed to the base, and 30 are provided with up-turned portions carrying finger keys 15. A cross bar 16 is mounted in the base beneath the key levers and a series of U-shaped springs 17 extending between this cross bar and the key levers hold 35 the latter in normal, raised position against the stop flange 18 at the upper front portion of the base.

40 A series of U-shaped bails 19, preferably six in number, are mounted within the base beneath the central portions of the key levers. The rearwardly extending arms of the bails are mounted upon pivot pins 20 (see Figs. 2 and 3) that are carried in brackets 21 fixed to and depending from the 45 top of the base. The bails are preferably

inclined downwardly and forwardly from the pivot pins 20 and U-springs 22 interposed between the cross bar 16 and the arms of the bails uphold the latter against a series of lugs 23 fixed to the key levers. The 50 lugs 23 are variably arranged upon the key levers so that each key will operate a different combination of bails in accordance with the character or signals represented thereby. Each key is, however, provided 55 with a lug for operating the first bail 19' at the front of the series.

The inner pivoted ends of the bail arms at the left-hand side of the machine are provided with a series of vertical arms 24 (see 70 Figs. 1 and 2) which project upwardly through an opening 25 in the top of the base. A series of bell crank levers are pivotally mounted upon a stud 26 rising from the base plate at one side of the opening 25, the bell crank levers being spaced apart by washers 27. Each of these bell crank levers comprises a forwardly extending arm 29 and a laterally extending arm 28. The arms 28 are progressively of different 75 lengths, the upper arm being the longest and the arms 24 are of progressively different heights, the left-hand arm being the highest, and the latter arms are provided with notches as indicated with dotted lines in 80 Figs. 1 and 2 for engaging the ends of the arms 28 so that the latter are variably operated in accordance with the operation of the key levers. The arm 24' which is connected to the outer bail 19' engages the upper arm 28' and this arm is not provided with a forwardly extending portion. Instead, it is provided with a rearwardly projecting lug 30 which carries an insulated 85 spring contact 31. This contact co-operates 90 with an insulated contact screw 32 which is adjustably mounted in bracket 33 projecting upwardly from the base.

95 The forwardly projecting arms 29 actuate a series of five punch controlling bars 34 which are pivoted to the forward ends of the arms. These punch controlling bars extend laterally from the arms 29 through a series of guide grooves formed in an oscillating punch actuator 35, the latter being 100 mounted at its right-hand end upon a vertical pivot stud 36 that projects upwardly from the base 10. A bar 37 fixed to the front face of the punch actuator 35 extends over the front edges of the punch controlling bars 110

34 and holds the latter in place relatively to the punch actuator. In this construction, the bars 34 oscillate with the punch actuator 35 but are free to be moved longitudinally, 5 independently of the punch actuator by the bell crank arms 29. The punch actuator is operated by a double spool, solenoid magnet 38 mounted on a bracket 39 that projects upwardly from the base plate. The cores 10 40 of this magnet are connected at their rear ends by a cross bar 41, and a push rod 42 is adjustably fixed to the center of the cross bar 41 and extends forwardly therefrom. The forward end of this push rod extends 15 through an opening in the bracket 39 and engages the rear face of the punch actuator 35. A spring 43 is connected to the punch actuator 35 and extends rearwardly therefrom to a stud 44 on the base. This spring 20 serves to hold the punch actuator in normal retracted position and in engagement with a stop screw 45 which is adjustably mounted on the bracket 39.

A hollow punch-holding bracket 46 is 25 mounted upon the base in front of the punch actuator and carries a number of horizontal punches 47 arranged in vertical series. The punches are preferably guided in openings formed in hardened steel plates 48 that are 30 fixed to the front and rear faces of the punch holder. The several punches are provided with enlarged portions 49, the forward ends of which are engaged by a stripper-plate 50. A spring or springs 51 interposed between 35 the stripper-plate and the front portion of the punch holder normally hold the punches in retracted position with the rear ends of the enlarged portions 49 engaging the rear guide plate 48.

40 The punches coöperate with a suitable die plate 52, which is secured to the front guide plate 48. The opposing faces of these plates are recessed to form a guide-way for the tape. The base of the machine is provided 45 with an opening 53 immediately below the row of perforators in the die plate 52, and a U-shaped shield 54 fixed to the base extends upwardly above the opening 53 and in front of the die plate 52, so that portions 50 punched from the tape are directed downwardly through the opening 53. The shield 54 may be readily moved to permit the removal of the die plate for sharpening.

The forward working end of one of the 55 punches, that is, a punch 47', is preferably smaller than the forward working ends of the other punches and is designed to form a longitudinal row of perforations in the tape that are adapted to be engaged by a suitable feed wheel. The rear end of this punch is 60 longer than that of the other punches so that it is invariably operated by the punch actuator 35 at each operation of the machine. The other punches are arranged in line with the punch controlling bars 34 that are vari-

ably controlled, as described, by operation of the finger keys. When the controlling bars are in the normal position shown in the drawings, the punches will be operated upon the forward movement of the punch actuator 70 35, effected by the solenoid magnet 38. But when one or more of the punch-controlling bars 34 are withdrawn or moved to the right by the operation of one of the finger keys, the corresponding punch or punches will 75 not be operated. As already noted, each key is arranged to operate the bail 19' which operates arm 28' through the medium of the arm 24'. The contacts 31 and 32 are thus closed whenever a finger key is depressed. 80 These contacts control the circuit of the punch-actuator magnet 38, and, when any key is depressed, one or more of the punch-controlling bars 34 is withdrawn from normal position and the circuit of the magnet 85 38 is closed to effect the operation of the punch actuator. In this way, transverse rows of perforations are punched in the tape to represent the different characters or signals, and, at the same time, a longitudinal 90 row of perforations are formed in the tape for engagement with a suitable feed-wheel.

The roll of unpunched tape is carried upon a rotatable holder 55 at the upper right-hand portion of the base. From the holder the tape passes over the end of a spring-held tension arm 56 and thence through the guide-opening between the die plate 52 and the guide plate 48. Thence the tape passes over a portion of the periphery 10 of a feed-wheel 57 which is provided with short rounded pins or teeth for engaging with the row of longitudinal perforations in the tape formed by the punch 47'. This feed-wheel is fixed to a shaft 58, which is 10 journaled at its lower end to the base 10 and at its upper end in a bracket 59 on the base. A press roller or wheel 60 is journaled in the U-shaped bracket 61 and the latter is pivotally mounted on a vertical shaft or pivot pin 11 62 fixed at its ends to the base and to the bracket 59. A spring coiled by the pivot pin or shaft engages the bracket 61 and forces the wheel 60 toward the feed-wheel 57. The wheel or roller 60 is provided with seats corresponding to the pin piece of the feed-wheel, and the spring held press roller serves to hold the tape in secure engagement with the feed-wheel.

The lower portion of the feed-wheel 57 1 is provided with ratchet teeth 63, which are arranged to be engaged by a pawl 64. This pawl is pivoted on an extension or lug 65 on the end of the punch actuator and extends forwardly therefrom and a spring 66 1 extending between the actuator and pawl hold the latter against the ratchet 63. The pawl is so arranged that, upon the forward or working stroke of the punch actuator, it moves idly over the ratchet 63 but advances

the latter and the feed-wheel and tape one step when the punch actuator is drawn back by its spring 43. Below the base top, the shaft 58 of the feed-wheel is provided with 5 a pointed-toothed retaining wheel 67 (see Fig. 3), which is arranged to be engaged by a dog to hold the feed-wheel against accidental movement. In the construction shown, the retaining dog preferably 10 comprises an arm or bell crank 68 pivoted at 68' to the under-side of the base top and having a roller on its end for engaging the wheel 67. A spring 69 yieldingly holds the retaining dog in position to prevent the 15 movement of the feed-wheel, but the teeth of the retaining wheel 67 are so shaped that this wheel may be forcibly moved both in forward and backward directions.

A back-space feeding device is provided 20 for the feed-wheel and comprises an arm 70 pivotally mounted upon the feed-wheel shaft 58 and immediately above the ratchet wheel 67. The forward end of the arm or lever 70 extends through a slot in the base 25 and a spring 71 connected to its rear end holds it in normal position. A dog or pawl 72 is pivoted on the arm 70 and is connected thereto by a spring 73. This dog is arranged to coöperate with the ratchet wheel 30 67, but, in the normal position of the parts, it is held out of engagement with the ratchet by a fixed pin 74 projecting downwardly from the base top through a slot in the lever 70. The lever 70, as most clearly shown 35 in Figs. 4 and 6, is also provided adjacent its pivot with an upwardly projecting pin 75 which extends through a slot 76 in the base top, and is arranged to engage a pin 77 that depends from the outer end of the 40 feed pawl or dog 64.

In operating the back-spacing device, the forward end of the arm or lever 70 is moved to the right to thereby bring its dog 72 into engagement with the ratchet 67. At 45 the same time the pin 75 on the lever 70 engages the pin 77 on the forwardly feeding dog 64 and moves the latter out of engagement with the ratchet 63. In this way the tape can be moved rearwardly or toward the 50 right and an improperly punched portion can again be brought into line with the punches. To correct the improperly punched portion, a special key of the machine serves simply to close the circuit of the actuator 55 magnet 38, so that all of the punches are operated to thereby rub out improperly perforated portions of the tape. The feed wheel is also arranged to actuate a suitable signaling device so that the operator may 60 know when sufficient characters have been perforated to constitute a line. For this purpose the lower end of the feed-shaft 58 is provided with a pinion 78 which is connected through the medium of an idle pinion 79 with a gear wheel 80. The latter

(see Figs. 3 and 4) is rotatably mounted on a stud 81 that depends from the base top. A plate 82 is fixed to the lower end of the stud and abuts against the hub of the gear 80 and a coiled spring 83 is fixed to this 70 plate and to the gear 80 and holds the latter in initial position with a pin 84 thereon against the end of an arm 85. The latter is mounted on a pivot stud 86 and is provided with a tail-piece 87. A spring 88 connected with the tail-piece holds the arm in normal position with the tail-piece engaging a stop pin 89. A spring contact 90 on the arm 85 is arranged to coöperate with a contact screw 91 adjustably mounted on a 80 bracket 92 on the under-side of the base at the top.

The idle pinion 79 is mounted upon the end of an arm 93, which is pivoted on the stud 81 above the gear 80. (See Figs. 3 and 4.) This arm is pivoted to one end of a transverse rod or link 94 which extends laterally therefrom, the opposite end of the link being connected to the short arm of a bell crank 95. The bell crank is pivoted 90 in a bracket 96 on the underside of the base top, and its long arm is arranged to be engaged by the extreme right-hand key lever 12. A spring 97 connected to the rod 94 (see Fig. 6) holds the parts in normal position with the idle pinion 79 engaging the pinion 78. A pivoted lock pawl 98 is arranged to coöperate with the notch 99 in the link 94 and a spring 100 tends to force the pawl toward the link. In the position 100 of the parts as shown in the drawings, the pawl is held in disengaged position by a stud 101 on the upper face of the gear 80.

The parts are shown in the position assumed when the operator commences to 105 punch the characters in the tape representing a line. As the operation proceeds, the gear 80 is rotated step by step in the direction indicated by the arrow in Fig. 3. Near the end of a single revolution, the pin 84 on the gear engages the side of the arm 85 and the contacts 90 and 91 are engaged to operate a suitable signal. In the construction shown, they serve to light a small electric lamp 102 which is mounted within the front extension 11 of the base beneath an opening 103 therein, so that the operator is then notified that sufficient characters have been punched in the tape to constitute a full line. He will then operate the special key which 110 punches the tape in correspondence with the carriage return signal. This special signal is represented by the key which operates the bell crank 95 so that the link 94 is moved 115 to the left to disengage the idle pinion 79 from the pinion 78. The spring 83 then serves to restore the counting wheel 80 to the initial position shown in the drawings. The lock pawl 98 coöperates with the link 94 to hold the idle pinion 79 disengaged 120 125 120

until the counting wheel 80 completes its return movement. The pin 101 on the wheel then disengages the pawl 98, and the spring 97 moves the pinion 79 back into mesh with the pinion 78. The counting wheel 80 is preferably mutilated as shown, so that it can only be moved in forward direction through nearly a single revolution, and the signal lamp will remain lighted until the operator 10 depresses the character return key.

It is obvious that numerous changes may be made in the details set forth without departure from the essentials of the invention as defined in the claims.

15 We claim as our invention:—

1. In a perforator for telegraph tape, the combination of a tape feed, a set of punches, a common actuator for said punches and said tape feed, a set of controlling members 20 interposed between said punches and said actuator, a set of bell-cranks for shifting said controlling members, a set of pivoted bails having arms thereon directly engaging said bell cranks, and a series of finger keys 25 for variably actuating said bails and controlling the operation of said actuator, substantially as described.

2. In a perforator for telegraph tape, the combination of a tape guide, a feed wheel 30 for the tape adapted to engage a longitudinal row of perforations therein, a punch adapted to form said row of perforations, a set of selectively operative punches, all of said punches being arranged in a row 35 transverse to the path of movement of the tape, a common pivoted actuator for all of said punches, a series of controlling bars mounted on said actuator to shift therewith, a set of bell cranks connected to said bars 40 to shift the same longitudinally into and out of operative position, an electro-magnet for operating said actuator, an operating pawl for said feed wheel mounted on said actuator, a set of bails having arms connected 45 to said bell cranks, a series of keys for variably operating said bails, and an additional bail uniformly operated by said keys for controlling the circuit of said magnet.

3. In a perforator for telegraph tape, the combination of a set of punches, a series of 50 finger keys variably controlling the operation of said punches, a feed wheel for intermittently advancing the tape, actuating devices for said feed wheel controlled by said 55 finger keys, and a back-spacing device for turning said feed wheel in reverse direction to thereby move punched portions of the tape back into the line with said punches.

4. In a perforator for telegraph tape, 60 the combination of a tape guide, a set of punches, a common actuator for said punches, a set of controlling members interposed between said actuator and said punches, a series of finger keys controlling 65 the operation of said actuator and said con-

trolling members, a feed wheel for the tape, means controlled by said actuator for operating said feed wheel to advance the tape in uniform distances at each operation, and a back-spacing device for rotating said feed 70 wheel in reverse direction.

5. In a perforator for telegraph tape, the combination of a tape guide, a set of punches, a common actuator for said punches, a set of controlling members interposed between said actuator and said punches, a series of finger keys controlling the operation of said actuator and said controlling members, a feed wheel for the tape, a pawl for advancing said feed wheel operatively connected to said actuator, and a manually operative back-spacing member having a pawl thereon for turning said feed wheel in reverse direction, said back spacing member having means for throwing said feed 85 pawl out of operative position.

6. In a perforator for telegraph tape, the combination of a tape guide, a set of punches, a common actuator for said punches, a set of controlling members interposed between said 90 actuator and said punches, a series of finger keys controlling the operation of said actuator and said controlling members, a feed wheel for the tape, two ratchets connected to said feed wheel, a normally engaged feed 95 pawl connected to said actuator and coöperating with one of said ratchets to advance said feed wheel, and a back-spacing lever having a normally disengaged pawl arranged to coöperate with the other of said 100 ratchets for reversing the movement of said feed wheel, said back spacing lever having means for disengaging said normally engaged feed pawl.

7. In a perforator for telegraph tape, the combination of tape punching mechanism, tape feed devices, a set of finger keys controlling the variable operation of said punching mechanism and the uniform operation of feeding devices, a counting member actuated 110 by said feeding devices, a switch operated by said counting member after a predetermined movement thereof, an electric signal controlled by said switch, and means controlled by one of said finger keys for restoring said 115 counting member to normal position.

8. In a perforator for telegraph tape, the combination of a set of punches, a feed wheel for intermittently advancing the tape, a set of finger keys for controlling said punches, a means controlled by said finger keys for intermittently advancing said feed wheel, a spring held counting wheel geared to said feed wheel, a switch actuated by said counting wheel after a predetermined movement 120 thereof, and means controlled by one of said finger keys for disengaging said counting wheel from said feed wheel to permit the return movement of said counting wheel to 125 normal position.

9. In a perforator for telegraph tape, the combination of a set of punches, a feed wheel for intermittently advancing the tape, a set of finger keys for controlling said punches, means controlled by said finger keys for intermittently advancing said feed wheel, a counting, mutilated gear wheel normally connected to said feed wheel, a switch controlled by said counting wheel after a predetermined movement thereof, a signal controlled by said switch, a member actuated by one of said finger keys for disengaging said counting wheel from said feed wheel, and a spring for restoring said counting wheel to a normal position.
10. In a perforator for telegraph tape, the combination of a tape guide, a feed wheel for the tape arranged to engage a longitudinal row of perforations therein, a set of selectively operated punches arranged in a row transverse to the path of movement of the tape, a common pivoted actuator for said punches, a series of controlling bars shiftable with said actuator and normally arranged in operative position between said punches and said actuator, a set of levers connected to said controlling bars to shift the same longitudinally out of operative position, a set of bails operatively connected to said lever, a series of finger keys for variably operating said bails, means controlled by each of said keys for operating said actuator, and a pawl for actuating said feed wheel and connected to and operated by said actuator.
11. In a perforator for telegraph tape, the combination of a vertically disposed tape guide, a set of selectively operated punches arranged in a vertical series transverse to the path of movement of the tape, a common actuator for said punches, a vertical series of controlling bars, a vertical series of levers connected to said controlling bars to shift the same horizontally into and out of operative position between said punches and said actuator, a set of finger keys, a series of bails variably operated by said keys and having arms thereon connected to said levers, and means controlled by each of said finger keys for effecting the operation of said actuator.
12. In a perforator for telegraph tape, the combination of a vertically disposed tape guide, a feed wheel for the tape adapted to engage a longitudinal row of perforations therein, a set of selectively operated punches arranged in a vertical series transverse to the path of movement of the tape, a common actuator for all of said punches, an actuating pawl for said feed wheel connected to and operated by said actuator, a vertical series of controlling bars mounted on and shiftable with said actuator, a vertical series of bell cranks connected to said bars to shift the same horizontally into and out of operative position, a set of bails, said bails and said bell cranks having inter-engaged arms of varying lengths, a set of finger keys for variably operating said bails and means controlled by each of said finger keys for operating said actuator.
